United States Patent Office.

C. THURSTON CHASE, OF ALBANY, NEW YORK.

Letters Patent No. 72,367, dated December 17, 1867.

IMPROVED SCHOOL-DESK AND SEAT.

The Schedule referred to in these Letters Patent and making part of the same.

TO ALL WHOM IT MAY CONCERN:

Be it known that I, C. THURSTON CHASE, of Albany, in the county of Albany, and State of New York, have invented a new and improved School-Desk and Seat; and I do hereby declare the following to be a full, clear, and exact description of the same, reference being had to the accompanying drawing, forming part of this specification, and which drawing represents a perspective view of my invention.

In this invention the seats and desks are so supported that each one is connected with all before and all behind it in the row. The same construction which effects this object renders the seat much easier to enter and leave. The seats are also provided with hinged bottoms, opening upward and inward.

In the drawings, A represents the desk, and B B' C C' the seats used in my improved method of constructing and arranging them for school-houses. Each desk is designed for two scholars, and is provided with two seats C C'. Each desk is supported upon three legs or standards—two, *a a*, in front at the ends of the desk, and one, D, under its rear edge at the centre, projecting downward and backward, so that the front edge of the seats C C' rests against it, as shown in the drawings. This method of construction possesses the advantage over all others hitherto in use, that it enables the wooden desk to be made with a wide open space at its ends, between its supports and the supports of the seat used in connection with it, so that the scholar can enter and leave his seat with ease. It also possesses the advantage that it tends to separate the occupants of adjoining seats, and prevents noise and confusion in the school. Each pair of seats C C' is supported upon three legs—two, *c c*, supporting the rear edge and back of the seat, the third being the rear standard, D, of the desk A in front of the seat. Each pair of legs *c c* is connected by a cross-bar, *e*, and provided with two horizontal arms *i i*, for the outer end of the seat-bottoms to rest upon. From the centre of the cross-bar *e*, a horizontal bar, *o*, extends to the post D, being firmly fastened at each of its ends, and designed for a support to the inner ends of the seat-bottoms. The bottom of each seat C C' is hinged to this bar *o*, so that their outer ends can be lifted up to a vertical position, as shown in the front seat B.

I make the seats and hinges so that the bottoms will slightly pass the vertical, in order that they may not fall back by their own weight. The seat-bottoms are thus designed to be elevated, in order to afford the scholar an easier access to his seat, and to enable him to stand comfortably at his desk.

It is obvious that the standards *c c*, which are represented as supporting the back of the seats C C' will, when the row of desks and seats is extended, become the front standards *a a* of the next desk in the rear. The whole series of desks and seats in a row will thus be firmly connected together, thereby greatly promoting their strength and stability. In single desks and seats, the standard D will be placed at one end.

Having thus described my invention, what I claim as new, and desire to secure by Letters Patent, is—

The combination and arrangement of the standard D with the hinged seats C C', horizontal bar *o*, and desk A, substantially as and for the purposes set forth.

To the above specification of my improvement I have signed my hand, this 29th day of October, 1867.

C. THURSTON CHASE.
